COAL MINING APPARATUS

Gideon D. Miller, Springs, Pa.

Application April 29, 1935, Serial No. 18,943

2 Claims. (Cl. 262—22)

The present invention relates to driving mechanism for coal undercutting machines, more particularly of the type having a bank of power driven augers extending forwardly from a wheeled carriage, although it may be modified for application to other types of machines.

In machines of the auger type, it is desirable to have power driving means for advancing the augers into the coal as the cutting progresses.

The drives hitherto used on this type of which I am aware have necessitated an anchor of some sort, as a mine prop, or a chain anchored to the walls, against which a push or pull could be exerted by the machine. When such anchors can be properly secured these types of drives are satisfactory, but where, due to the size of the tunnel or room, or the condition of the walls, difficulty is met with in providing a point against which the machine can exert a thrust, they are of course objectionable. Furthermore machines of this type have to be pushed from place to place, and as they may be quite heavy, this is often a difficult task.

One object of this invention is to provide a machine having an improved type of driving mechanism by which the supporting wheels of the machine are driven.

Another object of the invention is to include in the driving mechanism means whereby the travel of the machine may be reversed, in order that the augers may be withdrawn from the coal, or that the machine may be backed out of a narrow tunnel.

Another object is to provide such a mechanism having provision for more than one forward speed.

Still another object is to provide means for disconnecting one of the wheels from the other so that they may run at different speeds, in order to allow the machine to be turned.

Another object is to provide a novel driving mechanism which will permit the height of the augers with relation to the wheels to be adjusted.

In the accompanying drawings:

Figure 1 is an elevation of an undercutting machine equipped with the preferred embodiment of the invention.

Figure 2 is a plan showing the driving mechanism.

Figure 3 is a sectional view taken on the line 3—3 of Figure 2.

Figure 4 is a sectional view taken on the line 4—4 of Figure 2.

Figure 5 is a sectional view taken on the line 5—5 of Figure 4.

Figure 6 is a sectional view taken on the line 6—6 of Figure 4.

Figure 7 is a sectional view taken on the line 7—7 of Figure 4.

Figure 8 is a sectional view taken on the line 8—8 of Figure 4.

Figure 9 is a sectional view taken on the line 9—9 of Figure 3.

Figure 10 is a perspective view of the portion of the vertical adjustment device that is secured to the carriage.

Figure 11 is a perspective view of the portion of the vertical adjusting device that is secured to the axle.

Figure 12 is a perspective view of the guides for the vertical adjusting device.

Figure 13 is a perspective view of the spacing device for adjusting the distance between the driving mechanism and the wheels.

Figure 14 is a side elevation showing a modified form of driving wheels.

Describing the drawings, the coal undercutting machine includes a carriage 11 which may include side plates 12, a bearing support 13 and a top 14. Upon the top is mounted a gear box 15 in which is a system of gears through which a motor 16 drives the forwardly extending augers 17.

In the form shown in Figures 1—3 the carriage is supported by a pair of ground engaging wheels 18 mounted upon sleeves 19 which are rotatable upon stub axles 20. Each of the axles 20 extends horizontally from a vertically disposed dovetail member 21 slidably engaged between a pair of guides 22 which may be bolted to the side plates 12 of the carriage.

Each of the members 21 bears at its upper end an inwardly projecting ear 23 having a threaded opening 24 therein. The ears 23 enter through slots 25 into tubular members 26 mounted upon the top of the carriage, the members 26 being so positioned that the openings 27 in their tops lie directly over the threaded openings 24 in the ears when the members 21 are engaged between the guides 22.

Threaded rods 28 are swiveled in the openings 27 and project downwardly through the tubular members 26 and bear upon the top 14 of the carriage. The upper ends of these rods bear crank handles by means of which the rods may be turned. It will be appreciated that, inasmuch as the wheels 18 support the carriage through the lugs 23 and rods 28, turning the rods will raise or lower the carriage with respect to the ground. In order to drive the wheels 18, the fol-

lowing mechanism is provided. Power is obtained from the motor 16 by extending rearwardly the spindle 30 that drives one of the augers, in the form of a stud 31 projecting from the gear box 15. Upon the stud 31 is mounted a bevel gear 32, the opposite sides of which mesh respectively with bevel gears 33 and 34 rotatably mounted upon a jack shaft 35. The jack shaft 35 may be supported between one of the side plates 12 and the bearing support 13 of the carriage. The gears 33 and 34 constantly rotate in opposite directions, the gear 33 being used as a reverse, and the gear 34 being used as a forward driving gear.

Describing the forward drive, the gear 34 through a gear wheel 36 revolving with it upon the jack shaft 35, drives a gear wheel 37 mounted revolutely upon a countershaft 38.

The countershaft 38 extends transversely of the machine and beyond the side plate 12 in each side, being journaled in the side plates and in the bearing support 13 through which it passes.

A gear 39 revolves with the gear 37 upon the countershaft 38, and the gear 39 in turn drives a gear 40 mounted on the jack shaft 35 and revolute with respect to both the shaft 35 and the gear 36. Turning with the gear 40 is a gear 41 which drives a gear 42 revolute upon the countershaft 38 and revolute also with respect to the gear 37.

The gears 37 and 42 are provided on their relatively outward faces with toothed hubs 43 and 44 respectively, and these are engageable with toothed clutch members 45 and 46 respectively, which members are splined to the shaft 38 and are longitudinally slidable thereon. The mechanism for operating these clutch members will be described later. When the gear 37 is clutched to the shaft 38, the drive is directly through gears 34 and 37. Gears 39, 40, 41, and 42 constitute a system of reduction gearing through which the wheels 18 may be driven more slowly than through the direct drive. As will appear later, the clutch members 45 and 46 are so controlled that they are not engageable at the same time.

The reverse gearing is a duplicate of the higher speed forward drive. The bevel gear 33 is constantly driven in the opposite direction to the bevel gear 34. Through the pinion 47, secured to it, the bevel gear 32 drives a gear 48 revolutely mounted on the countershaft 38 and having a toothed hub for engagement with the toothed side of the clutch member 45 opposite to that engaging the hub 43.

The clutch members 45 and 46 are controlled by the shifting mechanism best shown in Figures 4, 5, and 6. Slidably mounted in brackets 49 depending from the top 15 of the carriage and separated by a member 50 secured to one of the side walls 12 and the bearing support 13, are two shipper bars 51 and 52. Attached to these bars are forks 53 and 54 engaging respectively the clutch members 46 and 45 and moving them into and out of engagement with the toothed hubs in response to longitudinal motion of the shipper bars. The shipper bars 51 and 52 have transverse channels 55 in their top portions, these channels being arranged to register with each other and with a similar channel 56 in the member 50 when the clutch members 45 and 46 are both in their neutral or disengaged position, shown in Figure 4.

The movement of the shipper bars 51 and 52 is controlled by a lever 57 mounted for movement in any direction by means of a ball and socket joint 58 which supports the lever upon the

top 14 of the carriage. The lower extremity of the lever 57 engages selectively the channels 55 of the shipper bars, and the channel 56 allows it to be moved from one to the other when the clutch members are in their neutral position. Preferably the lower end of the lever 57 has a ball 59 thereon for ease in moving it, and the upper end may be provided with a handle portion.

To allow the driving wheels 19 to rotate at different speeds, as is necessary in making turns, the countershaft may be made in two sections, which may be connected or disconnected by means of a collar 60 surrounding a portion of both sections, but keyed to only one of them and having a toothed end 62, and a collar 63 having a toothed end 64 for engagement with the end of the collar 61 and longitudinally shiftable on the other section and secured against relative rotation with that section by splines. The shifting of the collar 63 may be controlled by a shipper lever 65 pivoted to the top 15 of the carriage.

The driving wheels 18 are driven from the countershaft 37 through a mechanism which permits compensation to be made for variations in the distance between the shaft 37 and the wheels 18 due to the vertical adjustment of the carriage 11 by means of the crank handles 29. These mechanisms, at each end of the countershaft are duplicates, so only one will be described.

Outwardly of the side plate 12 of the carriage is a U-shaped bracket 66 having legs 67, the outer of which bears an extension 68. The legs of the bracket 66 are pivoted upon the countershaft 37 which passes through them. A gear wheel 69 mounted upon the countershaft, drives a gear wheel 70 mounted upon and keyed to a shaft 71 journaled in the extension 68 of the bracket. Mounted upon the shaft and rotating therewith is a sprocket wheel 72 which through a sprocket chain 73 drives a sprocket wheel 74 mounted upon the sleeve 19 of one of the wheels 14.

It will be apparent particularly from Figure 1 that as the distance between the countershaft 37 and the axle 20 varies, due to vertical rectilinear adjustment of the wheels, the bracket 67 will swing about the countershaft to properly adjust the tension of the sprocket chain 74, the gears 69 and 70 always remaining in mesh.

In order that this adjustment may be positive, a turn buckle 75 is provided, one end of which is connected to the axle 20 and the other end to the shaft 71 which runs in a bearing 76 provided in the end. Adjustment of the turnbuckle serves to space the axle 20 upon which the sprocket wheel 74 turns, and the shaft 71 upon which the sprocket wheel 72 is mounted, so that the sprocket chain 73 may be kept properly taut.

In the modification shown in Figure 14, a caterpillar belt 77 is provided for the machine 60 to travel upon. In this modification the wheels 18 which drive the belt 77 are mounted upon axles 79 which are vertically adjustable with relation to the carriage 80 in exactly the same way as the axles 20. Upon each of the adjustable members 81 which corresponds to the members 21 is secured a rearwardly extending support 82 at the rear extremity of which is rotatably mounted a cogged wheel 83 between which and the wheel 18 the belt 77 runs. Between the two wheels an idler wheel 84 is mounted upon the support 82 which engages the lower reach of the belt and runs along it during the travel of the machine.

The wheels 18 are driven in the same manner

as the wheels 19 by sprocket chains 85 which in turn are driven by sprocket wheels 86 mounted and driven in the manner of the wheels 72 shown in Figures 1, 2, and 3.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. In a coal mining machine, having a carrier, driving wheels mounted on the carrier, a plurality of forwardly extending augers and means for operating the augers, a spindle extending rearwardly from one of the augers, a jack shaft having two gears revolvably mounted thereon, said gears being driven in opposite directions by the said spindle, a countershaft, a plurality of gears for driving the countershaft at different speeds in one direction revolvably mounted on the coun-

tershaft and driven by one of the gears on the jack shaft, and a gear for driving the countershaft in another direction revolvably mounted on the countershaft and driven by the other gear on the jack shaft, means for selectively clutching any one of the gears mounted on the countershaft to the countershaft, and means operatively connecting the countershaft and the driving wheels.

2. In a coal undercutting machine having a carrier and power driven coal undercutting means, the combination with driving wheels supporting the carrier and relatively vertically adjustable with respect thereto, of a countershaft mounted on the carrier and driven by the coal undercutting means, a sprocket wheel support revolvably mounted on the countershaft, a sprocket wheel carried by the support and driven by the countershaft, and a strut adjustable in length and spacing the sprocket wheel support from the driving wheel for keeping the sprocket chain tight irrespective of the position of the driving wheel relative to the sprocket wheel.

GIDEON D. MILLER.
